UNITED STATES PATENT OFFICE.

JOHN W. CRAIG, OF BERNE, INDIANA.

DOOR-CHECK.

1,288,523.

Specification of Letters Patent. Patented Dec. 24, 1918.

Application filed April 20, 1918. Serial No. 229,799.

To all whom it may concern:

Be it known that I, JOHN W. CRAIG, a citizen of the United States of America, and resident of Berne, in the county of Adams 5 and State of Indiana, have invented certain new and useful Improvements in Door-Checks, of which the following is a specification.

This invention relates to builders' hardware and particularly to door checks.

An object of this invention is to provide novel means for arresting a door prior to its reaching the sill or frame so as to prevent slamming of the door, yet allowing the 15 said door to gradually close without the application of undue force.

A further object of this invention is to provide a resiliently held member coacting with a novel device movable with the door 20 and adapted in its swinging movement to engage or release a projecting member constituting one element of the check whereby the checking member would be reset as the door swings open and made operative as 25 the door swings to a closed position.

A still further object of this invention is to provide a check of the character indicated having novel means for increasing or diminishing the resistance of the check, thereby 30 making it applicable to doors of different weights or for operating under different conditions.

With the foregoing and other objects in view, the invention consists in the details of 35 construction, and in the arrangement and combination of parts to be hereinafter more fully set forth and claimed.

In describing the invention in detail, reference will be had to the accompanying 40 drawings forming part of this specification, wherein like characters denote corresponding parts in the several views, and in which—

Figure 1 illustrates a view in perspective 45 of the door check in position for operation;

Fig. 2 illustrates an underneath plan view of the check;

Fig. 3 illustrates a sectional view thereof; and

Fig. 4 illustrates a transverse sectional view.

In these drawings 10 denotes a rectangular

casing having a guiding core or partition 11, (to be hereinafter termed a core) therein, the said core having a recess 12 extending 55 diagonally of one end and a recess 13 extending diagonally of the opposite end and on the opposite side from that having the recess 12, the said recesses constituting clearances, as will presently appear.

The core may be constructed in any appropriate way, that is to say, it may be integral with the case or it may be a separate piece as the requirements of practice may dictate.

A leaf spring 14 is anchored as at 15 to the inner wall of the case and has its free portion lying in the recess 12 with its extremity 16 projecting beyond the end of the core 11.

The space between the core 11 and the sides and ends of the case constitute a race way for the check 17 which moves in a circuitous path around the said core, being engaged by the springs 14 and 18, as will 75 presently appear. The spring 18 is anchored as at 19 to a sliding member 20 and having movement in the casing, the said sliding member carrying a bow spring 21, whose ends 22 and 23 may bear against a 80 follower 24 so that the tension of the spring may be increased or diminished for the purpose of increasing or diminishing the action of the spring 18, since the said spring 18 affects the action of the check and offers a 85 greater or less resistance to the check, according to the adjustment of the follower. Screws 25 and 26 are threaded in the wall of the casing and bear against the follower so that the said follower may be forced inward or may be allowed to yield under the pressure of the spring 21.

The spring 18 has its free portion extending through or lying in the recess 13 and its extremity 27 lies in the way in which the 95 check travels, the said check, in the present embodiment of the invention, having a head 28 lying outside of the casing and connected to the check 17 by a neck 29, which neck travels in a slot 30 restricted in width as 100 compared with the check way of the body.

In forming the slot 30, the face plate 31 of the body has an aperture and the core 11 has a plate 32 attached to it, the said plate

being smaller than the aperture in the face plate and being disposed in such relation to the edge of the aperture of the face plate as to form the slot 30. One end 33 of the 5 plate 32 has a beveled edge and the edge of the opening in the face plate facing the edge of the plate 32 is correspondingly shaped, so that the slot 30 at one side of the plate 32 is longer than the slot at the 10 other edge thereof, whereas the slot at one end of the face plate is diagonal with respect to the slot at the opposite end of the said plate 32, so that the check will traverse the path of the slot in its operation.

15 The face plate has recesses 34 and 35 constituting seats for buffers 36 and 37 respectively, adapted to receive the impact of the check as it is moved under the influence of the springs or under the influence of the 20 door. The casing has a base 38 by which fastenings, such as 39, may be employed for attaching the said casing to a door frame or object, with relation to which the door moves.

25 A bracket adapted to be attached to a door comprises a base 40 secured to the door, at its upper edge, and the said base has an approximately horizontally disposed flange 41 with a slot 42 therein, the said slot having flanged edges 43 and 44 for engaging the check head 28, so that one of said flanges is operative to move the check head outwardly as the door swings open, and the other of said flanges is operative to engage the said 35 head upon closing of the door, thereby carrying the check in the outwardly extending parallel portions of the slot 30 according to the direction of movement of the door. The check is moved laterally across the ends of the 40 core by the springs 14 and 18 and the spring 18 is relied upon for arresting or partially arresting the check as it moves in the slot under the influence of the door when closing, the tension of the spring being proportional 45 to the weight of the door or the work to be performed during the checking operation.

From an inspection of the drawing, and from the foregoing description, it will be seen that when the door opens, the check 50 will be moved from the position in which it is shown in Figs. 2 and 3 to the opposite end of the core 11 and that the spring 14 will then force it transversely across the end of the core and that upon closing the door, 55 the check will be forced down or inwardly along the slot or way on the opposite side of the core until it engages the spring 18 which will yield according to the tension and that when the door is closed, the free 60 end 27 of the spring will return the check to the position in which it appears in Figs. 2 and 3, for a repetition of the operation.

I claim

1. In a door check, a member having a

core therein spaced from the inner walls 65 thereof to form a way, a spring anchored to the casing and extending across the way on one side of the core and terminating beyond the end of said core, a support for a spring, a spring attached to said support 70 and extending across the way on the side of the core opposite that occupied by the first mentioned spring, said second mentioned spring extending beyond the end of the core and projecting into the way, a check traveling in the way and adapted to engage the springs, and means for holding the check in operative relation with the springs while being moved.

2. In a door check, a member having a 80 core therein spaced from the inner walls thereof to form a way, a spring anchored to the casing and extending across the way on one side of the core and terminating beyond the end of said core; a support for a spring, 85 a spring attached to said support and extending across the way on the side of the core opposite that occupied by the first mentioned spring, said second mentioned spring extending beyond the end of the core and 90 projecting into the way, a check traveling in the way and adapted to engage the springs, means for holding the check in operative relation with the springs while being moved, and means for tensioning the 95 support of the second mentioned spring.

3. In a door check, a member having a core therein spaced from the inner walls thereof to form a way, a spring anchored to the casing and extending across the way on one side of the core and terminating beyond the end of said core, a support for a spring, 100 a spring attached to said support and extending across the way on the side of the core opposite that occupied by the first mentioned spring, said second mentioned spring extending beyond the end of the core and projecting in the way, a spring carried by the support of the second mentioned spring, 105 means for regulating the tension of the 110 spring of the support, a check traveling in the way and adapted to engage the springs, and means for holding the check in operative relation with the springs while being moved.

4. In a door check, a member having a core therein spaced from the inner walls thereof to form a way, a spring anchored to the casing and extending across the way on one side of the core and terminating beyond the end of said core, a support for a spring, 120 a spring attached to said support and extending across the way on the side of the core opposite that occupied by the first mentioned spring, said second mentioned spring extending beyond the end of the core and projecting into the way, a check traveling 125 in the way and adapted to engage the

springs, means for holding the check in operative relation to the springs while being moved, and a bracket for attachment to a door, said bracket having a slot longitudinally thereof for operating the check.

5. In a door check, a member having a core therein spaced from the inner walls thereof to form a way, a spring anchored to the casing and extending across the way on one side of the core and terminating beyond the end of said core, a support for a spring, a spring attached to said support and extending across the way on the side of the core opposite that occupied by the first mentioned spring, said second mentioned spring extending beyond the end of the core and projecting into the way, a check traveling in the way and adapted to engage the springs, means for holding the check in operative relation to the springs while being moved, means for tensioning the support of the second mentioned spring, and a bracket for attachment to a door, said bracket having a slot longitudinally thereof for operating the check.

6. In a door check, a casing having a core therein spaced from the sides and ends to form a way, a check slideable therein, springs for controlling the action of the check, a check head carried by the check, a neck interposed between the check and head, a face plate for the casing having an opening therein, the edge of the opening constituting a guide for the said neck, a plate on the core spaced apart from the edge of the aperture of the face plate and forming therewith a slot, the edge of the said plate constituting a guide for the neck of the check, and means on a door for engaging a check head.

40. 7. In a door check, a casing having a core therein spaced from the sides and ends to form a way, a check slideable therein, springs for controlling the action of the check, a check head carried by the check, a neck interposed between the check and head, a face plate for the casing having an opening therein, the edge of the opening constituting a guide for the said neck, a plate on the core spaced apart from the edge of the aperture of the face plate and forming therewith a slot, the edge of the said plate constituting a guide for the neck of the check, means on a door for engaging the check head, and means for controlling the tension of one of the springs.

55. 8. In a door check, a casing having a core therein spaced from the sides and ends to form a way, a check slideable therein, springs for controlling the action of the check, a check head carried by the check, a neck interposed between the check and head, a face plate for the casing having an opening therein, the edge of the opening constituting a guide for the said neck, a plate on the core

spaced apart from the edge of the aperture of the face plate and forming therewith a slot, the edge of the said plate constituting a guide for the neck of the check, means on a door for engaging a check head, means for controlling the tension of one of the springs, and means on the door for operating the check.

9. In a door check, a member having a core therein spaced from the inner walls thereof to form a way, a spring anchored to the casing and extending across the way on one side of the core and terminating beyond the end of said core, a support for a spring, a spring attached to said support and extending across the way on the side of the core opposite that occupied by the first mentioned spring, said second mentioned spring extending beyond the end of the core and projecting into the way, a check traveling in the way and adapted to engage the springs, means for holding the check in operative relation with the spring while being moved, and means for controlling the tension of one of the springs.

10. In a door check, a member having a core therein spaced from the inner walls thereof to form a way, a spring anchored to the casing and extending across the way on one side of the core and terminating beyond the end of said core, a support for a spring, a spring attached to said support and extending across the way on the side of the core opposite that occupied by the first mentioned spring, said second mentioned spring extending beyond the end of the core and projecting into the way, a check traveling in the way and adapted to engage the springs, means for holding the check in operative relation with the springs while being moved, means for tensioning the support of the said second mentioned spring, and means on the door for operating the check.

11. In a door check, a member having a core therein spaced from the inner walls thereof to form a way, a spring anchored to the casing and extending across the way on one side of the core and terminating beyond the end of said core, a support for a spring, a spring attached to said support and extending across the way on the side of the core opposite that occupied by the first mentioned spring, said second mentioned spring extending beyond the end of the core and projecting into the way, a check traveling in the way and adapted to engage the springs, means for holding the check in operative relation with the springs while being moved, means for controlling the tension of one of the springs, and means on the door for operating the check.

12. In a door check, a member having a core therein spaced from the inner walls thereof to form a way, a spring anchored to

the casing and extending across the way on one side of the core and terminating beyond the end of said core, a support for a spring, a spring attached to said support and extending across the way on the side of the core opposite that occupied by the first mentioned spring, said second mentioned spring extending beyond the end of the core and projecting into the way, a spring carried by the 10 support of the second mentioned spring,

means for regulating the tension of the spring of the support, a check traveling in the way and adapted to engage the springs, means for holding the check in operative relation with the spring while being moved 15 and a bracket for attachment to a door, said bracket having a slot longitudinally thereof for operating the check.

JOHN W. CRAIG.
